UNITED STATES PATENT OFFICE

2,184,711

ARRANGEMENT OF MAIN BOILERS FOR STEAMSHIPS

Olaf Damsleth, Tonsberg, Norway, assignor to
Kaldnes Mek. Verksted A/S, Tonsberg, Norway

Application November 16, 1937, Serial No. 174,872
In Norway November 25, 1936

1 Claim. (Cl. 114—0.5)

In steam ships the main boilers are generally placed on the bottom of the ship or, in accordance with some later constructions, even on the deck, in both cases, however, in such a manner that the distance between the boilers and the ship's bottom or the deck or platform supporting the boilers has been limited to the height necessary for supervision and repair.

In accordance with the present invention the
10 boilers are mounted on columns or supports in
such a manner that the access for supervision
and repair of the underside of the boilers is made
easy and practical, whereas on the other hand
the higher parts of the engine room on both sides
15 thereof is utilized for taking up the boilers in-
stead of being used for bunkers or not being
used at all, as the extra machinery placed on the
bottom of the engine room does generally not re-
quire the full height of the latter.

20 In accordance with the present invention it
will therefore be possible to restrict the space
necessary for machinery, so that the cargo holds
of the ship may be correspondingly increased.

On the drawing a diagrammatic cross section
25 of the ship serves to illustrate how the boilers

may be placed in accordance with the invention.

1 is the driving engine and 2, 3 the main boil-
ers. These are located on opposite sides of the
driving engine and are supported by columns 4
and 5 and by brackets 6, 7, mounted on trans-
verse wall sections 8, 9 in such a manner that
the underside of the boilers will be at a sufficient
height above the bottom of the engine room to
permit free movement below the boilers, respec-
tively to permit placing below the boilers of dif-
ferent kinds of supplementary machinery, as dia-
grammatically indicated at 10.

The lateral spaces between the transverse
wall sections 8, 9 may be utilized as storing rooms
or for other purposes.

I claim:

A power plant for steamships comprising a
main engine, two main boilers therefor located
on opposite sides of said engine with their axes
extending in the longitudinal direction of the 20
ship and columns supporting said boilers at such
a height above the engine room floor so that the
undersides of said boilers are readily accessible
and there is a free space below said boilers.
